UNITED STATES PATENT OFFICE.

WILLIAM HENRY FAY, OF CHESTER, MASSACHUSETTS.

APPARATUS FOR EXHIBITING PHOTOGRAPHS.

Specification forming part of Letters Patent No. 43,299, dated June 28, 1864.

To all whom it may concern:

Be it known that I, WILLIAM H. FAY, of Chester, in the county of Hampden and Commonwealth of Massachusetts, have invented a new and useful Photographic Table; and I do hereby declare that the following is a full, clear, and exact description of the same, reference being had to the accompanying drawings, making a part of this specification.

My invention consists of a table or other similar article of furniture so constructed as to receive pictures and protect them from injury, and also conveniently expose them to view. As here shown, the table is more especially designed for receiving the small card-photograph at present so common, and may be arranged to hold two concentric rows of pictures instead of one row, as here shown.

In the drawings making a part of this specification, Figure 1 is a perspective view of the table with the cover or top raised, so as to show the picture-holder. Fig. 2 is a top view of the table. Fig. 3 is a section of the top of table.

Like letters of reference indicate the same parts in each of the several figures.

A is the standard or frame of table.

B is a stationary top attached to standard A.

C is a rotary top above the top B, and attached to it by a pivot, a, through the center.

D is a cover or false top, hinged at the back to B, and so arranged as to shut down over and conceal the rotary top C and stationary top B, if desirable. The periphery of C is provided with the projections b b b or corresponding notches.

F is a spring attached to the inside of the cover D, and having its point pressing against the periphery of C.

G is another spring, attached to the knob or handle H, which moves in a slot, d, in the side of cover D.

The top of C is arranged to receive pictures and hold them in place by some convenient method. As here shown, the triangular pieces c c c are attached to the top of C through their centers, leaving their edges unattached, so that a card-picture can be inserted under their edges and thereby held in place.

The particular device for confining the pictures is immaterial, as they may be tacked on,

if more convenient. Now, the cover D is provided with one or more openings, I, in which a glass may be inserted. When the cover D is shut down and held in place by the catch L or any other suitable device, of course a portion of the top of C is visible through the opening I, and consequently if the top of C is covered with pictures one of the pictures may be seen through I.

The operation of my invention is as follows: The cover D being shut down, and the picture or pictures visible through the opening or openings I having been examined, to show a new picture, slide the knob H back till the spring G passes one of the pins b b b in the periphery of C; then return it to its first position, and the end of the spring G, operating against the pin b, turns the picture-holder C on its pivot a. The slot d is made of such a length that the table C will be rotated just the angular distance from the center of one picture to the center of the next one. Now, as C is rotated by moving the knob H forward in the direction indicated by the arrow, the stationary spring F is so situated as to catch in behind a pin, b, at the same time that the knob H reaches the end of the slot, and thus the rotary table C is prevented from turning back when the knob H is moved back preparatory to again rotating the picture-holder forward. Thus a common article of furniture is made a very interesting and novel feature in a drawing-room or parlor without in the least detracting from the ordinary utility of the same.

Now, having fully described the construction and operation of my invention, what I claim as new, and desire to secure by Letters Patent, is—

1. The cover D, having one or more openings, I, in combination with the rotary picture-holder C, when they serve to form the whole or a part of the top of a table or other similar article of furniture, substantially in the manner and for the purpose herein set forth.

2. The combination of cover D, rotary picture-holder C, stationary spring F, and spring-slide G, substantially in the manner and for the purpose described.

WILLIAM HENRY FAY.
